UNITED STATES PATENT OFFICE.

ALBERT J. RICHARDSON, OF LONG BEACH, CALIFORNIA, ASSIGNOR OF ONE-HALF TO
JAY LYLE, OF LONG BEACH, CALIFORNIA.

AUTOMATIC TIME CUT-OFF.

1,150,453.

Specification of Letters Patent. **Patented Aug. 17, 1915.**

Application filed May 13, 1914. Serial No. 838,387.

To all whom it may concern:

Be it known that I, ALBERT J. RICHARDSON, a citizen of the United States, residing at Long Beach, in the county of Los Angeles and State of California, have invented a new and useful Automatic Time Cut-Off, of which the following is a specification.

This invention relates to that class of devices adapted to be operated by timing or 10 clock mechanism to throw a switch so as to cut out of an electric circuit or circuits electric lamps or other electrically operated devices.

An object of this invention is the production of a device of this character which will be simple in construction, positive in action and accurate and reliable in operation.

An important object of this invention is the provision of simple time cut-off means which will meet with the requirements of fire insurance underwriters.

Another object of this invention is the provision of automatic cut-off means comprising an ordinary alarm clock which can be applied to and removed from operative relation with the switch throwing mechanism so as to facilitate winding of the clock and setting of the alarm mechanism.

Simplicity and practicality are the key 30 notes of the invention and other objects and advantages may appear from the subjoined detail description.

The invention may be variously embodied and I have illustrated two forms.

35 The accompanying drawings illustrate the invention.

Figure 1 is a front elevation of a device embodying the invention, the switch box door being omitted and the bottom of said switch box being broken away for clearness of illustration. Fig. 2 is a sectional elevation substantially on line indicated by x^2 , Fig. 1. Solid lines indicate the parts in their circuit closing positions and dotted lines indicate said parts in their circuit opening positions. Fig. 3 is a plan view of Fig. 1, the clock being omitted and a portion of the switch box top being broken away for clearness of illustration. Fig. 4

is a front elevation embodying another form 50
of the invention.

First considering the form of invention shown in Figs. 1 to 3. The case is preferably of metal and may be of cast iron or the like and comprises a timing mechanism receptacle 1 in its upper portion and a switch-box or support 2 in its lower portion, and said case may be hung on any suitable support as a wall, not shown, by suitable means, there being provided for this purpose perforations 3 to receive suitable fastening means as screws or the like, not shown. 55 60

The receptacle 1 is provided with timing mechanism which may be in the form of an ordinary alarm clock 4 removably mounted in said receptacle and securely held therein against lateral movement by lugs 5 projecting up from the shelf receptacle floor or switch-box top 6 and designed to engage the legs 7 of the clock. 70

The clock 4 as is usual with such time pieces is provided, among its other features which are well understood and therefore need no detail description herein, an alarm-operated element in the form of a winding key 8 having a winged head 9 that is positioned in the lower part of and adjacent the back of the receptacle 1 when the clock 4 is seated in place as in Fig. 2. 75

The alarm winding key 8 as is usual in 80
clocks of this character is revolved in one
direction to wind the alarm and when said
alarm is set off turns in the opposite direc-
tion and is designed to engage and operate
a stop-arm or trigger 10 which normally is 85
yieldingly pressed toward the key by suit-
able resilient means as a spring 11 fastened
by headed pins 12, or the like, to the under
side of the box top 6; and said arm may be
provided with manually operated retracting 90
means in the form of a draw rod 13 which
connects at one end to said arm and has its
opposite end piercing the side of the re-
ceptacle 1 so as to be accessible from the out-
side of the case. 95

The stop-arm 10 extends downward from the receptacle 1 through an orifice 100 into the switch-box 2 and is provided at its

lower end with a pivot 14 projecting from the rear wall of the switch-box and the front edge of said stop-arm forms a stop 15 adapted to move laterally to and from the path of travel of a stop 16 formed by the rear edge of one arm of a switch operating lever 17 pivoted at 18 to a bracket 19 which projects forward from the rear wall of the switch-box; the other arm of said lever being angularly bent to form a horizontal trip 20 that tends to press forward, by reason of a coil tension spring 21, toward the circuit closing bar or bars 22 of a circuit closing device which, in the drawings, is shown as an ordinary knife switch 23 that is well understood and therefore needs no detail description herein. The trip 20 and bar 22 are spaced apart from one another when the switch is closed and the bar 20 is in the set position, see Fig. 2, so that said bar will receive a hammer-like blow to insure throwing of the switch even when the switch is inclined to stick. The switch shown is two point but it is understood that a three point switch can be used if desirable. The knife switch 23 may control one or more electric circuits and for that purpose may be provided with one or more circuit-closing bars 22 as occasion requires, it being obvious that such circuit closing arms when mounted side by side in the usual manner can all be engaged by the single trip 20 which will be made of appropriate length for that purpose. From the foregoing it is seen that the stop-arm 10 and lever 17 are relatively edgewise disposed and that their paths of travel intersect one another.

The circuit-closing bar 22 projects from the switch-box 2 through a slot 24 in the bottom 25 of the switch-box so that said arm may be externally operated by hand to open and close the switch in the usual manner.

The switch-box 2 is provided with a door 45 fastened in place by screws 27 or the like.

In practice, supposing the switch 23 of the device to be in circuit with electric lamps or other devices, not shown, from 50 which it is desired to cut off the electric current of said circuit so as, for instance, to discontinue the supply of electric current to said electric lamps, and considering the clock 4 to be properly wound up and running, the proprietor or attache of the establishment in which it is desired to switch off said lamps, or the like, will remove the clock 4 from its receptacle 1 and set the indicator 28 of the clock at the time it is desired for the device to operate and he will wind the alarm by turning the key 8, all of which is well understood in connection with alarm clocks; and he will then replace the clock in the receptacle in the position shown 55 in Fig. 2.

Before replacing the clock or before leaving the establishment said attache will close the circuit by operating the handle 29 of the circuit-closing lever 22 to move said handle and lever from the dotted line position A, Fig. 2 to the solid line position B, in the manner usual with operating knife switches. Now supposing, for example, that the attache has set the indicator 28 at the hour of twelve o'clock as indicated in Fig. 75 1, so that the alarm winding key 8 will operate at said hour, it follows that when the hands 30, 31 of the clock indicate twelve o'clock, the alarm key 8 will turn, causing the winged head 9 to trip the stop-arm 10, 80 thereby moving the stop 15 out of the path of travel of the lever 17, which will instantly be moved forward by the force of the spring 21 to push out the circuit-closing bar 22 and thus open the circuit and cause cessation 85 of operation of the lamps or other devices.

In the form of invention shown in Fig. 4 the winged head 9 of the alarm key engages a trigger 10' which is an extension of a switch lever 32 of a switch 33 of different form from the switch shown in Figs. 1 to 3 and operating differently than said switch, the switch 33 being a two point switch of the character, for instance known to the trade as Junior No. 5 switch, or the like. 95

The trigger 10' is moved in one direction and held in one position by a spring 34.

The operation of the form of invention shown in Fig. 4 will be clear from the preceding description of the operation of the 100 form shown in Figs. 1 to 3, the only difference being that in the form shown in Figs. 1 to 3 the trigger 10 forms a stop which is thrown out of commission by the alarm key 8 so that the switch can be thrown by the 105 force of the spring 21, whereas in the form shown in Fig. 4, the trigger 10' forms a positive means directly connected to the switch 33 to operate the same.

I claim:

In combination, a case comprising a switch-box having a top forming a support which top is provided with an orifice, timing mechanism mounted on said support and having a revolving alarm key, a switch 115 mounted in the switch-box and provided with a circuit-closing bar, a stop-arm pivoted in the switch-box and extending through the orifice and into the path of travel of the alarm key, a lever pivoted in 120 the switch-box, said lever and stop-arm being edgewise disposed relative to each other and the stop-arm being disposed edge-wise relative to the axis of the alarm key to form a stop for said lever, a spring to 125 hold the stop-arm toward the alarm key, said lever having an angularly bent arm to form a trip extending back of the handle of the switch and spaced apart from said handle when the switch is closed and the 130

trip is in the set position, and a spring to force the trip end of the lever forward when the stop-arm is moved out of engagement with the lever, the bottom of said switchbox having a slot through which the circuit-closing bar extends.

5 In testimony whereof, I have hereunto set

my hand at Los Angeles, California, this 8th day of May 1914.

ALBERT J. RICHARDSON.

In presence of—

JAMES R. TOWNSEND,
GEORGE H. HILES.
